UNITED STATES PATENT OFFICE.

ALVA E. RAVENSCROFT, OF LOS ANGELES, CALIFORNIA, ASSIGNOR TO C. R. KIERULFF & CO., OF LOS ANGELES, CALIFORNIA, A COPARTNERSHIP CONSISTING OF C. R. KIERULFF AND ALVA E. RAVENSCROFT.

SINGLE-DISK PAY-OUT AND TAKE-UP WIRE REEL.

Application filed June 23, 1923. Serial No. 648,295.

To all whom it may concern:

Be it known that I, ALVA E. RAVENSCROFT, a citizen of the United States, residing at Los Angeles, in the county of Los Angeles 5 and State of California, have invented new and useful Improvements in Single Disk Pay Out and Take-Up Wire Reels, of which the following is a specification.

This invention relates to reels for handling bundles or coils of wire in erecting telegraph lines, telephone lines, wire fences and the like.

An object of this invention is to provide improvements in reels whereby one man, or 15 where it is practical two men, can transport and handle the wire without a truck, and whereby one man may handle the reel in horizontal or vertical position.

In carrying out this invention I employ 20 a frame having rails that project forwardly and rearwardly of a reel that is mounted to revolve on said frame; said rails adapting the device for sled-like use or for litter-like use, and I have provided the top edges of 25 said rails with loops at their ends whereby attachments may be made to the frame for sliding it along the ground or for carrying it by hand, and also for hoisting the frame up a pole.

30 An object of this invention is to improve a reel adapted to the saving of labor and time, and affording a line carrier that only requires one man to operate where before five men were required. This device is 35 adapted to be provided with a brake which can be operated by a wing nut, and is also provided with a handle for turning the reel to pay out or take up the wire and the invention is so constructed that one man can 40 perform the work very easily by turning the reel with one hand and adjusting the brake with the other hand allowing the wire to feed as desired.

Another object of this invention is to provide 45 a sturdy construction allowing very rough usage, and the reel may be placed in a motor truck or wagon used by a construction gang of a telephone or telegraph company and upon reaching the scene of operation it is usually thrown off the truck instead of being lifted off and is also put to other rough usage, and an object is to provide a construction that will stand up well with-

out detracting from the operation of handling the wire.

55 The invention comprises the construction of the reel and its mounting on the litter-like frame.

Other objects, advantages and features of 60 invention may appear from the accompanying drawings, the subjoined detail description and the appended claim.

The accompanying drawings illustrate the invention.

65 Figure 1 is a perspective view of the appliance lashed to an electric pole with the wire bundle upright and the axis of the reel horizontal.

Fig. 2 is a perspective view of the appliance shown in Fig. 1.

70 Fig. 3 is a mid section on line α^3 , Fig. 5, of the device up-ended as in Fig. 1.

Fig. 4 is an enlarged fragmental and 75 partly sectioned detail on line α^4 , Fig. 5, illustrating the guide and lock.

Fig. 5 is an enlarged plan view of the device.

The reel is provided with a frame or carrier comprising parallel duplicate rails 1 on the opposite ends and reel side of which are bolted cast iron handles 2 by bolts 3. Said rails are connected by intermediate cross-bars 4, mortised in the rails and located far enough inwardly from the ends of the rails to allow the frame to be carried litter-wise. A diagonal bar 5 connecting the rails extends at one end beyond one of the rails and is provided at its middle with the post 6 which passes through the bar 5 and is fastened by the adjusting or locking nut 7.

80 On the top side of bar 5 is a bearing support 8, which in turn supports the axle 6 and forms a bearing for the reel 9. Each of the cross-bars 4 is provided with a longitudinal slot 10 on one side of the center and with a hole 11 on the other side as shown in Fig. 5 of the drawing. An eyebolt 12 extends through the slot 10 and has a chain 13, carried by the eye terminal of the bolt, and a winged nut 14 is adapted to tighten 90 the bolt.

95 In the hole 11, there is a bolt 15 which is provided at one end with a winged nut 16 and at its opposite end with a hook 17 for engagement with one of the links of the 100 chain, so as to support the frame in an up-

right position against a suitable support, for instance, post 18 around which the chain may be passed as shown in Fig. 1 of the drawings.

5 The reel 9 comprises a casting or thimble 19 is provided with a flange 20. At the base there is another flange 21 and at the top 22 there is a square to allow for a handle 23. The casting 19 fits over and rotates on the 10 spindle 6.

A sheet metal disc 24 is riveted to the flange 20 by rivets 25. In the disc 24 are 15 six radial slots 26 equally spaced as best shown in Fig. 5 of the drawing. In the slots 26 there are prongs 27 around which the wire is wound as shown in Fig. 1 of the drawing.

The prongs 27 are provided at one end with a winged nut 28 to allow for adjustment and to clamp the prongs.

The disc 24 is provided with holes 29 equally spaced to allow the wire guide and lock arm 30 to fit thereinto for locking the reel 9.

25 The wire guide and lock arm 30 comprises a shank 31 which fits on a post 32 that extends at right angles to the plane of the frame and is held firm by nuts 33 in that portion of the diagonal bar 5 which extends 30 beyond the rails. A set screw 34 holds the wire guide and lock arm 30 in place, and an eyelet 35 is used as a wire guide which is next to the shank 31. On the other end of the lock arm 30 is a stud 36 to fit into holes 35 29 in the disk for locking the reel as best shown in Fig. 4 of the drawings.

A brake is provided in the form of a rod 37 inclined at a slight angle, one end 38 forming a semi-circular loop around the 40 casting 19 between the flanges 20 and 21 and at the other end a winged nut 39 is provided to abut against a bracket 40 which is bolted to the extending end of bar 5, and the brake can be adjusted by the wing nut 39.

45 To keep the handle 23 from sliding off the top of casting 19, a cotter pin 41 is used.

The drawings show the device in two 50 positions, one being upright chained to an electric pole and another a horizontal position. It is understood it may be used in other ways.

To operate with this device, the attendant turns the handle 23 which in turn rotates the reel disc 24 taking up or winding the wire around the prongs 27; and the wire is guided by the wire guide and stop 30.

To prevent racing and to regulate the

speed of the reel, I provide a brake rod 37 with one end 38 partly surrounding the hub 60 of the casting 19, and the other end is held by a bracket 40 and a wing nut 39 which is used to adjust the brake rod 37 as may be desired.

The reel is locked by stopping the disk when one of the holes 29 is alined with the 65 axis of the stud 36, and the wire guide and lock 30 is released by loosening set screw 34, and is allowed to slide down the post 32 to insert the stud into the hole 29 and then the set screw 34 is tightened holding the 70 lock 30 firm and locking the reel. The coil of wire is then removed by releasing the wing nuts 28 on the prongs 27 and turning the prongs inwardly; and the coil of wire 75 is then lifted off the reel.

To mount the wire for unwinding, the coil is laid on the disc and the prongs are turned outwardly and slipped into position and clamped to hold the wire coil firmly. The operation of winding the wire is similar 80 to paying it out, except that the disc revolves in an opposite direction.

The cast iron handles 2 are in the form of rigid loops on the upper side of the frame and are sufficiently outside the rim of the 85 disk to allow a person between the rail to carry the end of the frame litterwise by the handles without any interference with the disk of the reel.

90 I claim.

The lineman's reel substantially set forth comprising a frame having rails; cross bars connecting said rails together; a diagonal bar connecting said rails and having one end extending beyond one of said rails; and axle 95 secured to said diagonal bar; a thimble rotatably mounted on said axle and having a flange and a squared portion; a disc secured to said flange; radially adjustable prongs secured to said disc; a post secured to the extending end of said diagonal bar; a wire 100 guide and lock arm carried by said post; a bracket secured to said frame; a rod having one end engaging said spindle and its other end extending through said bracket; and means abutting against said bracket to adjust the rod against said spindle.

In testimony whereof, I have hereunto set my hand at Los Angeles, California, this 16th day of June, 1922.

ALVA E. RAVENSCROFT.

Witness:

JAMES R. TOWNSEND.
